UNITED STATES PATENT OFFICE.

JAMES H. NORTHRUP AND MYRON J. BIGELOW, OF HOPEDALE, MASSACHUSETTS, ASSIGNORS TO THE DRAPER COMPANY, OF SAME PLACE AND PORTLAND, MAINE.

LOOM.

SPECIFICATION forming part of Letters Patent No. 595,198, dated December 7, 1897.

Application filed May 22, 1897. Serial No. 637,651. (No model.)

To all whom it may concern.

Be it known that we, JAMES H. NORTHRUP and MYRON J. BIGELOW, of Hopedale, in the county of Worcester and State of Massachusetts, have invented an Improvement in Looms, of which the following description, in connection with the accompanying drawings, is a specification, like letters and figures on the drawings representing like parts.

10 While it is customary to locate the belt fork or shipper and the shipper-handle at the same side of the loom—the usual practice—it is desirable at times to locate the shipper-handle at one side and the belt fork or shipper at 15 the other side, and in United States Patent No. 574,142 a construction is shown whereby such object is attained. In that patent a spring is employed to move the shipper in one direction, movement in the opposite direction being effected by or through a flexible connection between the shipper and the shipper-handle.

This present invention is an improvement on the construction shown in said patent, 25 whereby the spring is dispensed with and the shipper actuated in both directions by a positive connection with the shipper-handle, and the shipper-handle may be located at one side of the loom, with the belt fork or shipper 30 at the other, or both may be located at the same side of the loom.

Figure 1 is a vertical side elevation of a sufficient portion of a loom to be understood, embodying our invention, with the belt-fork and shipper-handle at the same side. Fig. 2 is a plan view of a portion of a loom, showing the application of our invention when the shipper-handle is at one side and the belt fork or shipper at the other side of the loom; 40 and Fig. 3 is a detached side view of the shipper-handle.

The loom-frame A, breast-beam A', lay crank-shaft B, the fast and loose pulleys B' B², respectively, on said shaft, and the pinion B³ are and may be of usual construction in looms.

Referring first to Fig. 2, the plate e' is extended from one side of the loom, having a slot e² and notch e³, the slot receiving the upper end of the shipper-handle b, fulcrumed on a bracket or stand b', secured to the loom

side. At the opposite side of the loom a stud a, projecting therefrom, receives a sleeve a', carrying the usual belt-fork a², an arm a³ on said sleeve traveling in a guide a⁴ on the loom side. The sleeve a' has a stud a⁵ thereon to engage one end of a bent rod d, extended through an opening in the loom side, and a link d' is rigidly secured to said bent rod at its inner end, as by set-screws 2. The link 60 is extended across the loom and through the opposite side frame and pivotally attached at d² to one end of a lever d³, fulcrumed at d⁴ on a stand d⁵, secured to the loom side. At its front end the lever d³ is bent up at d⁵, 65 and its preferably reduced extremity d⁶ is loosely inserted in a slot b² above the fulcrum b⁵ of the shipper-handle b. (See Fig. 3.) When the shipper-handle is released from the holding-notch e³, its spring S (see Fig. 1) will 70 throw it into the position shown in Fig. 2, and through the lever d³, link, and rod the belt-fork a² will be positively moved to shift the belt onto the loose pulley B². Movement of the shipper-handle into running position 75 will positively move the belt-fork to shift the belt onto the fast pulley B'.

Turning now to Fig. 1, the fast and loose pulleys are shown at the same side of the loom as the shipper-handle b, the loose pulley B² outermost, and the stud a, a sleeve a', and belt-fork a², with the guide a⁴, are also at the same side of the loom as the shipper-handle. The bracket d⁵ has pivoted thereon a lever d³⁰, pivotally connected at d²⁰ with the sleeve a'; but in this instance the front end of the lever is downturned at d⁵⁰, its extremity d⁶⁰ being extended into a slot b³ in the shipper-handle, below the fulcrum of the latter. Such difference in the point of connection between the lever and the shipper-handle will now cause the outer end of the lever to be swung inward when the shipper-handle is released from the notch e³, to operate the belt-fork, instead of being swung outwardly, 95 as in Fig. 2. This change is necessitated by the opposite movement of the belt-fork to shift the belt to the loose pulley B², which in each instance is outside of the fast pulley B', as usual.

To adapt the mechanism from the construction shown in Fig. 1 to that shown in Fig. 2,

the connecting-rod d and link d' are interposed between the belt-fork sleeve a' and the lever on the loom side, and the lever $d^3 d^5$ (shown in Fig. 2) may be also used by merely turning it upside down, as shown by dotted lines, Fig. 1.

Having fully described our invention, what we claim, and desire to secure by Letters Patent, is—

- 10. In a loom, a driving-shaft having fast and loose pulleys thereon at one side of the loom, a belt-fork adjacent said pulleys, means to support it, and a shipper-handle having slots therein above and below its fulcrum, combined with a reversible bent lever at the same

side of the loom as the shipper-handle and adapted to be connected at its rear end with the belt-fork and at its front end to enter one or other of the slots of the shipper-handle, whereby the belt-fork is positively operated by movement of the shipper-handle in either direction, substantially as described. 20

In testimony whereof we have signed our names to this specification in the presence of two subscribing witnesses.

JAMES H. NORTHROP.
MYRON J. BIGELOW.
